UNITED STATES PATENT OFFICE.

HARRISON BRAND, OF ILION, NEW YORK, ASSIGNOR TO A. M. ROSS & CO.,
OF SAME PLACE.

DESIGN FOR A GARDEN-TROWEL.

SPECIFICATION forming part of Design No. 23,226, dated April 24, 1894.

Application filed March 21, 1894. Serial No. 504,558. Term of patent 7 years.

To all whom it may concern:

Be it known that I, HARRISON BRAND, a citizen of the United States, residing at Ilion, in the county of Herkimer and State of New York, have invented a certain new Design for Garden-Trowels, of which the following is a specification.

My invention relates to garden trowels, and the invention consists of a design for the trowel.

Figure 1 is a front perspective view, and Fig. 2 is a rear perspective view.

The leading features of the design consist of a pointed blade B concave transversely on its front, and a handle H concave on its rear face, this handle where it unites with the blade terminating in a V shaped portion I, convex on its front face and concave on its

rear, all as clearly shown in the accompanying drawings. It will be observed that the 20 concavity of the handle is much greater than that of the blade, it constituting nearly a semi circle, and that the end of the handle is rounded off and curved backward on nearly the same line of curvature as the sides of the 25 handle as clearly shown in the figures.

What I claim is—

The design for a garden trowel herein described and shown.

In witness whereof I hereunto set my hand 30 in the presence of two witnesses.

HARRISON BRAND.
